LIFTING TRUCK

Application filed January 19, 1931. Serial No. 509,649.

This invention relates to lifting trucks for lifting and transporting stands on which goods are piled in a mill or shop from one place to another.

It is the object of this invention to provide a lifting truck of novel and improved design, which can be inexpensively made and can be readily operated.

To this end the invention consists in the novel parts and novel combinations of parts hereinafter defined in the claims and described in the following specification, made in connection with the accompanying drawings wherein like reference characters refer to the same or similar parts throughout the various views and, in which,

Fig. 1 is a plan view illustrating the lifting truck of the present invention;

Fig. 2 is a vertical section taken longitudinally of the truck on the line 2—2 of Fig. 1, as indicated by the arrows and illustrating certain of the movable parts in full lines in one position and in dotted lines in another position;

Fig. 3 is a view in end elevation of the truck; and.

Fig. 4 is a view in side elevation of the truck placed under a stand adapted to be lifted and moved by the truck, certain of the parts of the truck and the stand being illustrated in full lines in one position and in dotted lines in another position.

Referring to the drawings, in accordance with the present invention, there is provided a lower frame 4 which is preferably of rectangular shape and is of greater length than width. The frame 4 as illustrated, is formed from angle iron having vertical flanges forming the ends and sides of the frame and inwardly projecting horizontal flanges joining the vertical flanges at the upper edges thereof. Secured to the horizontal flanges of the frame 4 at the four corners thereof and below the horizontal flanges are plates 5 of substantially triangular shape, which plates serve to brace and strengthen the frame 4 and form seats upon which swivelled castors 6 are mounted. The castors 6 support the frame 4 in spaced relation from the floor or the ground and at the same time permit

the truck to be moved from one place to another and steered as it is moved. An upper frame 7 also preferably rectangular in shape is located above the frame 4 and is of the same length and width as is the frame 4. 55 The frame 7 is also preferably constructed from angle iron and has vertical flanges forming the ends and sides of the frame and inwardly projecting horizontal flanges joining the lower edges of the vertical flanges 60 and adapted to rest on the horizontal flanges of the lower frame 4 when the upper frame 7 is in lowered relation relative to the frame 4. Secured to the upper sides of the horizontal flanges of the upper frame 7 at the four 65 corners thereof, are plates 8 of substantially triangular shape and these plates serve to brace and strengthen the upper frame. Secured to the end horizontal flanges of the upper frame 7 adjacent the two sides of the upper frame are downwardly projecting pins 9, which extend through openings in the end horizontal flanges of the lower frame 4 and the lower plates 5. The pins 9 have reduced portions adjacent their upper ends which 70 project through the horizontal end flanges of the upper frame 7 and are fixed in the upper plates 8 and the reduced upper portions of the pins form shoulders which bear against the bottom surfaces of the end horizontal 75 flanges of the upper frame.

A pair of oppositely disposed bearings 10 are secured as by bolts 11 to the central portions of the horizontal side flanges of the lower frame 4 and a shaft 12 fits within these 80 bearings 10 and extends transversely below and between the sides of the lower frame 4. The shaft 12 projects beyond one side of the frame 4 and has secured thereto an arm 13 which serves as a handle for rocking the 85 shaft. A U-shaped stop member 14 secured to the same side of the lower frame 4 cooperates with the handle 13 to permit rocking movement of the shaft 12 through only slightly more than 180°. Cams 15 are mounted on the shaft 12 adjacent to but inwardly disposed from the sides of the lower frame 4. 90 Collars 16 are also mounted on the shaft 12 to prevent lateral shifting movement of the shaft. The collars 16 abut the bearings 10. 95 100

Transverse shafts or rods 17 are mounted in and extend between the vertical side flanges of the lower frame 4 adjacent but inwardly spaced from the ends of the frame. These 5 shafts 17 may be conveniently secured to the vertical side flanges of the lower frame by means of oppositely disposed jamb nuts 18 screw threaded on the shafts 17. Pairs of spaced collars 19 are mounted on the shafts 10 17 adjacent the ends thereof but inwardly disposed from the sides of the lower frame 4 and these pairs of spaced collars are preferably in substantial longitudinal alignment with the cams 15. Pivotaly mounted adjacent 15 each end of the two shafts 17 between pairs of collars 19 are levers 20 and each lever 20 has a short outer arm extending below and bearing against the lower end of one of the pins 9. Each lever 20 also has 20 a long inwardly extending arm terminating in a short upwardly extending cylindrical portion 20a which bears against the lower surface of one of the cams 15. The long inwardly extending arms of the levers 20 at 25 one side of the truck are so bent that the two cylindrical portions 20a thereof may both bear against a single cam 15, while similarly the long arms of the two levers 20 at the other side of the truck are likewise bent so that the two cylindrical portions 20a thereof may bear against the lower surface of the other cam 15.

In Fig. 4 there is illustrated a stand A adapted to be lifted and moved from one 30 place to another by means of the present truck. The stand A may consist merely of a horizontal supporting surface 21 upon which goods are adapted to be piled and spaced downwardly extending sides or legs 22 adapted to hold the supporting surface 21 in spaced relation above the floor or ground, so that the truck of the present invention may be run sideward below the supporting surface 21 and between the sides 22 when the 35 upper frame 7 rests on the lower frame 4. When the upper frame 7 of the truck rests on the lower frame 4, the cams 15 will be upwardly swung to the full line positions illustrated in Figs. 1, 2, 3 and 4. In this position the handle arm 13 will engage one side of the U-shaped stop member 14. Of course, the levers 20 will take the position illustrated in full lines Figs. 1, 2, 3 and 4. When the parts are in this position, the truck may 40 be run underneath the stand A, whereupon the arm 13 may be swung through slightly more than 180° to engage the other side of the U-shaped stop member 14. The shaft 12 will accordingly be rocked and the cams 15 will be 45 swung downwardly to the dotted line positions shown in Figs. 2, causing the long inner arms of the levers 20 to be depressed. The short outer arms of the levers will be raised and the pins 9 will also be raised there- 50 by lifting the upper frame 7 and the stand A

together with whatever goods may be piled upon the stand. The stand A will be raised so that the legs or sides 22 are clear of the ground or floor and the truck may then be pushed to the position desired, whereupon 70 the shaft 12 may be swung back to its original position to allow the stand to be again lowered to rest on the floor or ground and the truck can then be moved from underneath the stand. As the shaft is rocked from one 75 extreme position to the other, the cams 15 will be swung so that the points where the cylindrical portions 20a of the levers 20 engage the cams are slightly past dead center 80 when the cams are downwardly swung to the dotted line position. There will thus be no tendency when the upper frame 7 is once lifted for the upper frame to fall back again on the lower frame until after the lever 13 is swung in an opposite direction. 85

It will be seen that the lifting truck of the present invention is very simple in construction and in operation. But little force need be applied to the handle arm 13 to raise a heavily loaded stand A onto the truck due 90 to the use of the cams 15 and the long inner arms of the levers 20.

It will, of course, be understood that various changes may be made in the form, details, arrangement and proportions of the various 95 parts without departing from the scope of the present invention.

What is claimed is:—

1. A lifting truck comprising a lower wheeled frame, an upper frame normally resting on said lower frame, a shaft mounted in said lower frame, a cam carried by said shaft, levers pivoted in said lower frame and having arms bearing against said cam and arms bearing against portions of said upper frame, and means for swinging said shaft to rotate said cam and swing said levers to raise said upper frame from said lower frame. 100

2. A lifting truck comprising a lower wheeled frame, an upper frame normally resting on said lower frame, a shaft journaled in said lower frame, a pair of cams carried by said shaft, four levers pivoted to said lower frame, said levers each having an arm bearing against one of said cams and an arm extending to a point adjacent a corner of said upper frame and bearing against a portion of said upper frame and means for swinging said shaft to swing said levers and thereby raise and lower said upper frame relative to said lower frame. 110

3. A lifting truck comprising a lower frame mounted on wheels, an upper frame normally resting on said lower frame, pins secured to said upper frame and projecting downwardly 125 through openings in said lower frame, a shaft journaled in said lower frame and extending transversely thereof, a pair of cams mounted on said shaft, levers pivotally mounted on said lower frame and having arms extending 130

below and bearing against said cams and also having arms extending below and bearing against said pins and means for swinging said shaft to in turn swing said levers and thereby 5 raise and lower said upper frame relative to said lower frame.

4. A lifting truck comprising a castor equipped lower rectangular frame, a rectangular upper frame resting on said lower frame when in lowered position, pins mounted in said upper frame adjacent the four corners thereof and projecting downwardly through openings in said lower frame, a shaft journaled in said lower frame and extending 10 transversely and centrally thereof, a pair of shafts mounted respectively adjacent the ends of said lower frame and extending transversely thereof, pairs of levers pivotally mounted adjacent the ends of said last two 15 mentioned shafts and having inner arms extending below and bearing against said cams and having outer arms bearing respectively against the lower ends of said pins and means for swinging said first mentioned shaft.

20 25 5. The structure defined in claim 4 and stop means limiting the swinging movement of said first mentioned shaft to slightly more than 180°.

6. A lifting truck comprising a lower 30 frame of rectangular shape, castors supporting the four corners of said lower frame, an upper frame of rectangular shape supported on said lower frame when in lowered position, members secured to said upper frame 35 and projecting downwardly through openings in said lower frame, a transverse shaft centrally journaled in said lower frame, a pair of cams mounted respectively adjacent the ends of said shaft, a pair of transverse 40 shafts mounted in said lower frame adjacent the ends thereof, levers pivoted on said last mentioned shafts adjacent the ends thereof, the two levers adjacent similar ends of the two last mentioned shafts having inwardly 45 extending arms projecting below and bearing against one of said cams and the levers adjacent the other ends of the said two last mentioned shafts having inner ends bearing against the other of said two cams, the outer 50 ends of respective levers bearing against said respective members and means for swinging said first mentioned shaft.

In testimony whereof I affix my signature.
OLAV VIK.
